(57) **CLAIM**

The ornamental design for a lamp device, as shown and described.

DESCRIPTION

FIG. 1 is a perspective view of a lamp device showing our new design;

FIG. 2 is a front view thereof, the back view being identical to the front view;

FIG. 3 is a right side view thereof, the left side view being identical to the right side view;

FIG. 4 is a top plan view thereof;

FIG. 5 is a bottom plan view thereof;

FIG. 6 is a longitudinal cross-sectional view thereof taken along the lines VI—VI in FIG. 4;

FIG. 7 is an illustrative perspective view of the lamp device according to our new design received in a receptacle shown in broken lines for illustrative purposes only; and,

FIG. 8 is another illustrative perspective view of the lamp device of our new design received in a receptacle, shown in broken lines for illustrative purposes only and forming no part of the claimed design, the lamp device being pivoted around a longitudinal axis.
